CHARLES HARDY, OF NEW YORK, N. Y., ASSIGNOR TO AMSCO PRODUCTS, INC., OF NEW YORK, N. Y., A CORPORATION OF NEW YORK.

SELF-FILLING DEVICE FOR PENS.

Application filed March 6, 1926. Serial No. 92,763.

This invention relates to fountain pens, and has special reference to the provision of an improved self-filling device for fountain pens.

5 A principal object of my present invention comprehends the provision of an improved self-filling device for fountain pens of the type embodying a lever fulcrumed in the pen barrel and movable for actuating the sack deflating presser bar of the fountain pen filling mechanism. In known fountain pen fillers of this type the lever is located in a longitudinal slot in the pen barrel and is fulcrumed either directly in the walls of the 10 barrel slot or in a frame member which is attachable to for lining the said slot walls; and in the latter form of construction the lever and frame member are joined to constitute a unitary device which is removably 15 attachable to the pen barrel as a unit.

When the lever of the filling device is mounted or fulcrumed directly in the walls of the slot, the slot walls are exposed; and in some forms of construction, notably when 20 the barrel is made from a cellulose material, the exposed edges of the slot walls are unavoidably rough and uneven and present an unsightly appearance. In the form of construction wherein the lever is fulcrumed in 25 and carried on the frame member, forming therewith a unitary attachment for the barrel, the exposed walls or edges of the slot are in part concealed by the frame member thus 30 overcoming the disadvantage of the form of construction in which the lever is fulcrumed directly in the slot walls; but this unitary 35 lever and frame assembly construction possesses other disadvantages incident particularly to the manufacture and use of the same.

40 In the manufacture of these units the lever must first be assembled on the frame member, and this is usually accomplished by inserting a hinge pintle or pivot pin through the lever and side walls of the frame member and affixing 45 said pivot pin onto the frame member, the assembling of these parts being a difficult operation requiring manipulative skill due especially to the comparatively small dimensions of the parts or elements handled. In 50 use the small hinge pintle or pivot pin is placed under a substantial strain when the lever is moved to presser bar actuating position, and this results in the gradual distortion and loosening of the hinge pintle, with

the result that the lever oft-times works 55 loose and becomes detached from the frame, necessitating the replacement of both the frame and the lever by a new assembly or attachment. A principal object of my present invention comprehends the provision of 60 an improved self-filling device in which the disadvantages incident to and resulting from both of the referred-to forms of prior construction are obviated and the advantageous features thereof combined in an efficient 65 manner.

More specifically, the prime desideratum of my present invention centers about the provision of a self-filling device in which a 70 presser bar actuating lever is mounted or fulcrumed directly in the walls of the barrel slot while the said lever is associated with a frame member arranged in the slot for lining the exposed edge walls thereof, the frame member and lever comprising independent 75 elements separately attachable to the barrel of the pen, and associated so that the parts of the self-filling device may be assembled on the pen barrel with facility and rapidity and without the manipulative skill of an 80 operator and so that either of the lever and frame member elements is capable of being detached from the pen barrel for replacement or other purposes without disturbing the integrity of or detaching the other element from the pen barrel; the further provision of an improved self-filling device of 85 this nature in which the lever is ruggedly fulcrumed in the pen barrel by means which may be readily inserted through the slot 90 for detachably attaching the lever to the pen barrel; and the still further provision of an improved self-filling device of the nature referred to in which the parts are capable of being manufactured from sheet material by 95 quantity production methods to produce an efficient self-filling device saleable at a low figure.

To the accomplishment of the foregoing and such other objects as may hereinafter 100 appear, my invention consists in the elements and their relation one to the other, as hereinafter particularly described and sought to be defined in the claims; reference being had to the accompanying drawings which show 105 the preferred embodiments of my invention, and in which:

Fig. 1 is a top plan view of a pen barrel

showing the self-filling device of my invention assembled thereon,

Fig. 2 is a longitudinal elevational view thereof taken in cross-section in the plane of the line 2—2, Fig. 1,

Fig. 3 is an enlarged view thereof taken in cross-section in the plane of the line 3—3, Fig. 2,

Fig. 4 is a perspective view thereof showing the manner of assembling or disassembling the parts or elements of the self-filling device, and

Fig. 5 is a fragmentary cross-sectional view of the pen barrel and parts showing a modification.

Referring now more in detail to the drawings, and more particularly to Figs. 1 to 3 thereof, the improved self-filling mechanism of my invention generally designated as A is shown affixed to a fountain pen generally designated as B, the said fountain pen comprising a barrel 10, a removable pen-carrying member 11 which may be received by the barrel with a slip or screw fit, the said pen-carrying member having attached thereto the usual ink-carrying deflatable sack 12 with which cooperates a presser bar 13 of any suitable construction, the same being shown as a resilient member removably receivable by the inner wall of the barrel 10, the said presser bar being in longitudinal engagement with the ink sack 12 for depressing and deflating the same when operated by the self-filling mechanism A.

As heretofore stated, the prime object of the invention centers about the provision of a self-filling mechanism of the fulcrum lever type in which the lever for actuating the presser bar is mounted or fulcrumed directly in the walls of the barrel slot while the said lever is associated with a frame member arranged in the slot for lining the exposed edge walls thereof, the frame member and lever comprising independent elements which are separately attachable to the barrel of the pen and are associated so that the parts of the self-filling device may be assembled on the pen barrel with facility and rapidity and without that manipulative skill required in mechanism of prior manufacture, the construction being, moreover, such that either of the lever and frame member elements is capable of being detached from the pen barrel without detaching the other element from the pen barrel. To accomplish these results, the self-filling device A comprises a frame member 14 located in an elongated slot 15 provided in the wall of the pen barrel and attachable to the barrel as a separate element and a presser bar actuating lever 16 independent of the frame member 14 located in said slot 15 and mounted between the side walls of the frame member, the said lever being fulcrumed in the walls of the slot in a manner to be described more particu-

larly hereinafter, the lever and its fulcruming means being also attachable as a separate element to the pen barrel.

The separable frame member 14 is preferably made of a single sheet of material shaped or formed to include a top marginal lip portion 14' extending about three walls of the frame, as clearly shown in the drawings, and which functions to line the exposed edge walls 17, 17 of the slot 15, the frame member being attachable to the barrel by means of a plurality of spaced integral bottom lugs 18, 18 preferably two on each side of the frame, which lugs are inturned into engagement with the inner walls of the barrel at the slot or opening by means of a suitable implement manipulated from within the barrel after the frame member is placed or inserted in the slot. The frame member further includes an integral bridging portion 19 for bracing the frame structure and forming a suitable stop member for the lever 16, as shown for example in Fig. 2 of the drawing.

The lever 16 is also preferably made from sheet metal formed to define an arm 20 for ridingly engaging the presser bar 13 and an arm 21 adapted to be manipulated by the finger of the operator for actuating the self-filling device, the said lever being provided with registering apertures 22 for receiving the means for fulcruming the lever in the wall of the pen barrel 10. Preferably the means for fulcruming the lever is designed so as to permit the lever to be readily attached to and detached from the pen barrel, the fulcruming means consisting of an expansively resilient ring 23 which is readily inserted through the apertures 22, the said ring fulcruming means 23 being received by and seatable in a circumferential channel or groove 24 provided in the inner wall of the barrel 10. The lever 16 and fulcruming means 23 together form a unit or element which is attachable to the barrel independently of the attachment of the frame member thereto.

The parts of the self-filling device may be quickly and separately assembled onto the barrel by first attaching the frame member 14 in the manner described and by then inserting the spring ring 23 sidewise into the slot 15, and by thereafter turning the lever to snap the spring ring into position in the circumferential groove 24. To associate the parts to permit the independent attachment of the frame member and the actuating lever and to permit either of these separate elements to be detached from the barrel without disconnecting or detaching the other of the elements, the side walls of the frame member 14 are openingly cut away as at 25 about the portion of the fulcruming ring which bridges the gap or slot 15; and by means of this construction it will be seen 130

that the lever 16 and its fulcrum ring 23 may be inserted in the slot and mounted in position after the frame member has been attached to the barrel, and it will be further seen that the frame member may then be detached if desired without affecting the integrity of mounting of the lever element and that moreover the lever and its fulcruming means may be detached and withdrawn from the slot without dismantling or disconnecting the frame member.

By means of this recited construction, therefore, it will be evident that the separable parts of the self-filling device may be quickly and efficiently attached to the pen barrel without the exercise of any manipulative skill and without the necessity of handling the pivot pins or hinge pintles of small dimensions. It will be further evident that should the lever become broken in use, the same may be detached and replaced by a new lever element without the necessity of removing the frame member, thus economizing in the cost of replacement of parts. The frame member 14 is, moreover, capable of being constructed out of sheet metal so as to completely line, cover or conceal the marginal edge walls of the slot or opening 15, this being especially desirable where the pen barrel is fashioned or made from celluloid or the like, the edge walls thereof being subject to uneven contraction and expansion and presenting an unsightly appearance. Moreover, by means of the construction provided the lever is ruggedly fulcrumed in the pen barrel without weakening the walls of the barrel, a strong and durable construction being thereby produced.

Referring now to Fig. 5 of the drawings, I show a modification or improvement in which means are provided for serving as a motion-limiting device for the presser bar actuating lever, the parts of the self-filling device being otherwise the same as that shown in Figs. 1 to 4 of the drawings and being designated by like reference characters. For limiting the motion of the lever 16 in one direction without interfering with the separably detaching functions of the lever element and the frame element, I prefer to provide a second expansible resilient ring member 26 seated in a circumferential or annular groove 27, a portion of said ring 26 bridging the slot 15, the said ring being so disposed relatively to the lever 16 as to form a stop member therefor to limit the motion of the lever in the sack deflating position, as shown clearly in Fig. 5 of the drawings.

The manner of making and using the self-filling device of my invention and the advantages thereof will in the main be fully apparent from the above detailed description thereof. It will further be apparent

that while I have shown and described my invention in its preferred forms, that many changes and modifications may be made in the structure disclosed without departing from the spirit of the invention, defined in the following claims.

I claim:

1. A fountain pen comprising a barrel provided with an elongated slot in a wall thereof, a frame member lining the exposed edge walls of the slot, said frame member being attachable as a separate element to the barrel, an ink sack in the barrel, a presser bar for deflating the sack, a presser bar actuating lever independent of the frame member located in said slot and mounted between the side walls of the frame member, and means fulcruming the lever in the side walls of the slot, said fulcruming means and lever being also attachable as a separate element to the barrel.

2. A fountain pen comprising a barrel provided with an elongated slot in a wall thereof, a frame member lining the walls of the slot, said frame member being removably attachable as a separate element to the barrel, an ink sack in the barrel, a presser bar for deflating the sack, a presser bar actuating device independent of and separable from the frame member located in said slot and mounted between the side walls of the frame member, and means fulcruming the actuating device in the side walls of the slot, said fulcruming means and actuating device being also removably attachable as a separate element to the barrel.

3. A fountain pen comprising a barrel provided with an elongated slot in a wall thereof, a frame member in said slot attachable as a separate element to the barrel, the attaching means for the frame member including a top marginal lip portion lining the exposed edge walls of the slot and bottom lugs turned into engagement with the walls of the slot, an ink sack in the barrel, a presser bar for deflating the sack, a presser bar actuating lever independent of the frame member located in said slot and mounted between the side walls of the frame member, and means fulcruming the lever in the walls of the slot, said fulcruming means and lever being also attachable as a separate element to the barrel, the side walls of said frame member being cut out about said fulcruming means so that either of said separate elements may be detached from the barrel and withdrawn from the slot without disconnecting or detaching the other of said separate elements.

4. A fountain pen comprising a barrel provided with an elongated slot in a wall thereof, a frame member in said slot, said frame member being insertible in the slot and attachable as a separate element to the barrel, an ink sack in the barrel, a presser

bar for deflating the sack, a presser bar actuating lever independent of the frame member located in said slot and mounted between the side walls of the frame member, the inner wall of the barrel being provided with a circumferential groove, and a fulcruming ring for the lever seated in said groove, said fulcruming ring and lever being also insertible through the slot and attachable as a separate element to the barrel.

5. In combination with a fountain pen barrel having an elongated slot in a wall thereof, a frame member in said slot lining the exposed edge walls of the slot, said frame member being insertible in the slot and attachable to the barrel as a separate element, a presser bar actuating device independent of the frame member located in said slot and mounted between the side walls of the frame member, and means fulcruming the actuating device in the slot walls of the barrel, the fulcruming means and actuating device being also insertible through the slot and attachable as a separate element to the barrel, the side walls of said frame member being openingly cut away about said fulcruming means so that either of said separate elements may be detached from the barrel without detaching the other of said separate elements from the barrel.

6. In combination with a fountain pen barrel having an elongated slot in a wall thereof, a frame member in said slot lining the exposed edge walls of the slot, said frame member being insertible in the slot and attachable to the barrel as a separate element, a presser bar actuating lever independent of the frame member located in said slot and mounted between the side walls of the frame member, and a ring fulcruming the lever in the slot walls of the barrel, the inner wall of said barrel being provided with a circum-

ferential groove for removably seating the fulcruming ring, the fulcruming ring and lever being also insertible through the slot 45 and attachable as a separate element to the barrel, the side walls of said frame member being openingly cut away about said fulcruming ring so that either of said separate elements may be detached from the barrel 50 and withdrawn from the slot without detaching the other of said separate elements from the barrel.

7. In combination with a fountain pen barrel having an elongated slot in a wall 55 thereof, a frame member in said slot lining the exposed edge walls of the slot, said frame member being insertible in the slot and attachable to the barrel as a separate element, a presser bar actuating lever independent of 60 the frame member located in said slot and mounted between the side walls of the frame member, a ring seated in an inner groove of the barrel fulcruming the actuating lever in the slot walls of the barrel, the fulcruming 65 ring and actuating lever being also insertible through the slot and attachable as a separate element to the barrel, the side walls of said frame member being openingly cut away about said fulcruming ring so that 70 either of said separate elements may be detached from the barrel without detaching the other of said separate elements, and a second ring seated in an inner groove of the barrel bridging said slot, the said second 75 ring being disposed relatively to the said lever and its fulcruming ring to form a motion limiting device or stop for said lever in its operative or sack-deflating position.

Signed at New York city, in the county 80 of New York and State of New York this 17th day of February, A. D. 1926.

CHARLES HARDY.
